WITNESS:

UNITED STATES PATENT OFFICE.

EDWARD M. LOFTUS, OF ST. PAUL, MINNESOTA.

PLIERS.

1,398,904.

Specification of Letters Patent. Patented Nov. 29, 1921.

Application filed August 9, 1920. Serial No. 402,158.

To all whom it may concern:

Be it known that I, EDWARD M. LOFTUS, a citizen of the United States, residing at St. Paul, in the county of Ramsey and State of Minnesota, have invented new and useful Improvements in Pliers, of which the following is a specification.

This invention relates to improvements in pliers and has for an object the provision of 10 means for holding the jaws of the pliers against opening movement.

As is well known, a pair of pliers may often be advantageously used in the removal of nuts or the disassociation of devices except for the fact that it sometimes requires 15 more strength to hold the jaws of the pliers in operative position than is possessed by the workman, the leverage inserted in attempting to turn the nut or other member 20 acting to force the jaws open and thereby rendering the pliers useless for that purpose.

In order to overcome this leverage, the present invention aims to provide an attachment which is carried by the pliers and capable 25 of being moved into position to prevent opening movement of the jaws, so that the latter may be adjusted to a nut or other object and the attachment operated to hold the jaws against being forced open.

30 Other objects and advantages of the invention will appear as the following description is read in connection with the accompanying drawings.

In the drawings:

35 Figure 1 is an elevation of a pair of pliers with the invention attached thereto, the latter being shown in an inactive position.

Fig. 2 is a view similar to Fig. 1 showing the invention in use.

40 Fig. 3 is a sectional view on the line 3—3 of Fig. 2.

Fig. 4 is a detailed view of a modified form of the attachment.

45 Fig. 5 is a detailed view of another means for mounting the dog.

Fig. 6 shows a modified form of one end of the dog.

Fig. 7 is a view showing a further modification.

50 Referring in detail to the drawings wherein like characters of reference denote corresponding parts, the reference character 10 indicates the jaws of a pair of pliers which are pivotally secured together as shown at 55 11 and provided with operating handles 12.

As is usual in pliers of this character, the jaws are reduced at their point of pivotal connection so that the opposite faces of the pliers may be substantially flush and by thus reducing the thickness of the jaws a shoulder 13 is provided.

The invention resides in the provision of a dog 14 which is pivotally secured as shown at 15 upon one jaw of the pliers, the free end of this dog being preferably slightly 65 curved and roughened or serrated for engagement with the shoulder 13. The roughened or serrated end is also beveled so that the dog will engage the shoulder at various degrees of opening of the jaws. In order 70 to hold the dog against accidental pivotal movement, a spring washer 16 is interposed beneath the head of the pivot pin 15 and bears upon the face of the dog.

The pliers may be used in the usual manner with the dog in the position shown in Fig. 1, but when moved to the position shown in Fig. 2, any amount of leverage may be applied to the handles 11 without forcing the jaws open. It is preferred to provide the 75 jaw to which the dog is pivoted with an extension 17 to provide for a wider range of adjustment for the jaws.

In Fig. 4 there is illustrated a detailed view of one of the dogs 14. This is in all 80 respects similar to the dog shown in the other figures except that its free beveled end is straight instead of curved.

The invention is susceptible of various other changes in its form, proportions and 90 minor details of construction and the right is herein reserved to make such changes as properly fall within the scope of the appended claim.

Having described the invention what is 95 claimed is:

The combination with a pair of pliers having a pair of jaws pivotally secured together and provided with shoulders disposed transversely of their gripping ends, of a lateral 100 extension formed on one jaw adjacent the pivotal connection, a dog having one end pivotally secured to said extension and its opposite end beveled for adjustable engagement with the outer end of the shoulder of 105 the other jaw to limit the opening movement of the jaws.

In testimony whereof I affix my signature.

EDWARD M. LOFTUS.
